UNITED STATES PATENT OFFICE.

HIMES W. ROSENBAUM, OF NEW YORK, N. Y.

HAIR-RETAINING COMB.

SPECIFICATION forming part of Letters Patent No. 794,047, dated July 4, 1905.

Application filed January 25, 1905. Serial No. 242,650.

To all whom it may concern:

Be it known that I, HIMES W. ROSENBAUM, a citizen of the United States, residing in New York, borough of Manhattan, in the State of New York, have invented certain new and useful Improvements in Hair-Retaining Combs, of which the following is a specification.

This invention relates to hair-retaining combs, and has among its objects the provision of a comb of this type embodying means for securely retaining the same in the hair in order to prevent the displacement or loss thereof.

A further object of the invention is to provide a comb provided with an improved device for interlocking the comb and the retaining member in connection therewith, said device serving to securely position the parts, but being readily unlocked in order to release the comb from the hair.

With these and other objects and advantages in view the invention consists in a comb embodying the novel features which will be fully described hereinafter and finally pointed out in the claims.

In the accompanying drawings, Figure 1 is a rear elevation of a hair-retaining comb embodying the invention. Fig. 2 is a vertical transverse section of the same on line 2 2, Fig. 1. Fig. 3 shows a modified construction of the improved hair-retaining comb. Fig. 4 is a vertical transverse section on line 4 4, Fig. 3. Fig. 5 shows an ordinary hair-comb provided with my improved retaining device; and Fig. 6 is a vertical transverse section on line 6 6, Fig. 5.

Similar letters of reference indicate corresponding parts throughout the several views.

Referring to the drawings, *a* designates a hair-retaining comb of the usual concavo-convex form and provided with the usual teeth, which are inserted at the back or side of the head in order to hold the hair-dress in position. Connecting the ends of the back *b* of the comb is a transverse resilient retaining member *d*, which extends across the convex surface of the comb and is made

wider at its middle portion and thinner at its end portions, being preferably twisted near its connection with the back of the comb, as shown at *f* in Figs. 1 and 5, so that it exerts a spring action on the hair and teeth after the comb has been placed in position in the hair and holds thereby the comb in a reliable manner in position at the point at which it has been applied without any change or shifting of position in the hair. The transverse retaining member may be made integral with the back of the comb and bent over, as shown in Figs. 1 and 2, or it may be made of a separate piece extending over the back and cemented or otherwise attached thereto, as shown in Fig. 3. The back *b* is provided with a locking device *e* at its intermediate portion, as shown in Fig. 1, which is constituted by a resilient pin extending from the back and adapted to be snapped into position over the intermediate portion of the retaining member *d* after the comb is placed in position in the hair, so that the retaining member exerts a pressure on the hair and holds it firmly in the teeth of the comb. The locking device *e* may also be applied to the retaining member itself, extending downwardly and into a recessed portion of the back, as shown in Fig. 3. On relieving the locking device from its connection either with the retaining-piece or back of the comb the pressure on the hair is released, so that the comb can be readily removed from or replaced into the hair. The retaining member may also be applied to ordinary hair-combs either by being made in one piece with the same and bent over so as to form twisted ends with the combs, or the ends may be attached by rivets or otherwise to the head of the comb, its middle portion being retained by the locking device *e* after the comb is in place.

Having thus described my invention, I claim as new and desire to secure by Letters Patent—

1. A hair-retaining comb having a retaining member connected at both ends to the back thereof and extending across the teeth,

and means for locking said member in position against the latter.

2. A hair-retaining comb comprising a comb portion proper, a resilient retaining member connected with the ends of the comb portion and extending across the teeth of the same, and a device for locking said retaining member to the back of the comb.

3. A hair-retaining comb consisting of a comb portion proper, a retaining member made integral therewith and connected by twisted portions with the back of the comb, said retaining member extending transversely across the comb portion, and a locking device between the back of the comb and said retaining member.

4. A hair-retaining comb having a retaining member extending across the teeth thereof, and means acting upon the intermediate

portion of said member for locking the same 20 against said teeth.

5. A hair-retaining comb having a retaining member extending across the teeth thereof, and a resilient device for locking said member against said teeth.

6. A hair-retaining comb having a retaining member extending across the teeth thereof, and a pin extending from the back of the comb and operable to lock said member against said teeth.

In testimony that I claim the foregoing as my invention I have signed my name in presence of two subscribing witnesses.

HIMES W. ROSENBAUM.

Witnesses:

PAUL GOEPEL,
HENRY J. SUHRBIER.
